UNITED STATES PATENT OFFICE.

THOMAS F. KEAN, OF BOSTON, MASSACHUSETTS.

TAP.

No. 839,296.

Specification of Letters Patent.

Patented Dec. 25, 1906.

Application filed May 7, 1906. Serial No. 315,706.

To all whom it may concern:

Be it known that I, THOMAS F. KEAN, a citizen of the United States, residing in Boston, in the county of Suffolk and State of Massachusetts, have invented certain new and useful Improvements in Taps, of which the following is a specification.

This invention relates to a certain improvement in expanding taps for cutting the threads in nuts; and it has for its objects to provide new and improved means whereby as soon as the thread has been cut in the nut the cutters are automatically withdrawn from engagement with the nut and the nut can be quickly and easily removed without reversing its spiral movement or unscrewing it from the cutters, whereby this automatic release of the nut by the withdrawal of the cutters is accomplished when the tapping process reaches a predetermined point, and whereby in other respects the tap is rendered more efficient and its operation is facilitated.

The nature of the invention is fully described below and illustrated in the accompanying drawings, in which—

Figure 1 is a plan view of my improved tap with the cutters expanded into the position for cutting a screw-thread in a nut. Fig. 2 is a horizontal section of the same. Fig. 3 is a longitudinal vertical section illustrating the position of the parts when the cone is thrown back by the spring and the cutters are thus withdrawn sufficiently to allow the nut to be removed. Fig. 4 is a section taken on line 4-4, Fig. 2.

Similar letters of reference indicate corresponding parts.

a represents a cylindrical head provided with a back *b*, which is integral with the tail or shank *c*, whereby the device may be applied to or inserted in the turret of a turret-lathe. A front plate *d* is screwed at *e* to the front edge of the cylindrical head *a*. Supported centrally at its opposite ends in the front plate *d* and back *b* is a stud *g*, which supports slidingly a cone or frustum *h*. This cone is provided on its front edge with a deep annular groove *h'*, in which is located a spiral spring *k*. The peripheral surface of the cone is provided with radial dovetail grooves *l* of even depth throughout, and the cylindrical head *a* is provided with longitudinal radial slots *m* opposite or registering with the dovetail grooves *l* and of even thickness and length therewith. Within these slots *m* and extending down into the

grooves *l* are the radial cutters *n*, the lower ends of said cutters being dovetailed and in shape to correspond with the dovetail grooves *l*. The cutters are prevented from longitudinal movement by the rear ends of the slots *m* and the front plate *d*; but their dovetailed connection with the cone *h* is a sliding one. Inasmuch as the dovetail grooves in the cone are of even depth throughout and as the surfaces of the cutters are substantially parallel with the surface of the head *a* the cutters are longitudinally wedge-shaped, and hence if the cone were moved back and forth on the stud *g* the cutters would move outward and inward—that is, radially in the head *a*—the cone sliding with relation to the cutters, but the cutters having no longitudinal movement. In other words, the reciprocation of the cone horizontally within the head renders the tap expansive and contractive as regards its cutters.

The cone *h* is provided with two rearward parallel extensions *i*, Figs. 1 and 3, which project through suitable openings in the rear wall *b* along and parallel with opposite sides of the shank or tail *c*.

p represents a sliding carrier-arm whose hub *p'* is slidingly supported by the shank *c*, said arm being prevented from rotation by the rod *q*, which extends through it from the head. This arm is bored to receive a rod *r*, which constitutes a portion of a latch comprising said rod *r*, threaded to receive a nut *r'*, and a frame consisting of the tubular portion *s* in line with the rod *r* and the tubular portion *s'* at right angles therewith, the portions *r*, *s*, and *s'* being one integral piece. The tubular portion *s'* contains a bolt *u*, provided at its inner end with an integral hook or catch *u'* and centrally with a horizontal opening *v*, beveled at its rear edge, as shown in Fig. 2, and the tubular portion *s* is provided with a bolt *w*, slotted at *w'* to receive the pin *t*, extending from the portion *s* and beveled at its inner end to correspond with the beveled rear edge of the opening *v*. A spring *f* holds the beveled portion of the opening *v* against the beveled end of the bolt *w*, and the pin *t* in the slot *w'* limits the movement of the bolt *u*. A horizontal plate *j*, recessed at *j'* to receive the catch *u'*, is bolted to the head. A yoke-lever *x* is pivotally secured at *x'* to a post *z*, extending horizontally from the rear side of the head *a*, and this yoke-lever is provided with two projections *y*, whereby it may be swung by its handle *y'*.

against the flanged portions p^2 of the hub p' , and thus move said hub and carrier-arm toward the head and the extensions i into the head for the purpose below described.

- 5 The normal position of the tap is that illustrated in Figs. 1, 2, and 4, in which the yoke-lever $x y'$ has by means of its projections y , which bear on the flanges p^2 , forced the hub p' of the carrier-arm p toward the rear wall b of the cylindrical head a , said hub p' forcing in the extensions i , and thus moving the cone h toward the front plate d against the power of the spring k , as shown in Fig. 2. At the same time the carrier-arm p , moving with its hub p' , moves the latch mechanism forward into locked engagement with the recessed plate $j j'$, as indicated in Figs. 1 and 2. This forward movement of the cone h forces the cutters n radially outward to their fullest extent, thus expanding the tap into proper position for operating on the nut. The nut is moved up to the tap in the well-known manner and rotated, as usual, for the purpose of being tapped, and when during the tapping process the rotating nut reaches the outer end of the bolt w , it pushes it in, withdrawing the catch u' of the bolt u from the recessed plate $j j'$, and the spring k instantly forces the cone h back into the position indicated in Fig. 3, and the extensions p^2 force the hub p' and its arm p a distance beyond the back plate d which is equal to the distance moved by the cone, said hub also swinging the yoke-lever $x y'$ in the same direction. As the cone was thrown back by the spring k it necessarily withdrew the cutters n wholly or partially into the grooves m , as above described, thus leaving the nut entirely out of engagement with the cutters and free to be removed instantly without reversing its movement or imparting any rotation to it, saving, therefore, the time spent on reversing and unscrewing nuts from taps after they have been operated on. To re-45 place the tap in operative position, the yoke-lever is swung forward, carrying with it the hub and carrier-arm $p' p$, the extension i , and the latch mechanism, thus locking the latch mechanism and moving the cone into 50 the position indicated in Fig. 2, and the cutters outward into expanded position ready for use.

Having thus fully described my invention, what I claim, and desire to secure by Letters Patent, is—

1. In a tap of the character described, a head or case, a cone adapted to slide in said head, an extension connected with the cone and projecting through a wall of the head, 60 cutters extending through the peripheral wall of the head and adapted to be moved outward or expanded by the forward move-

ment of the cone, a latch mechanism adapted to be released at a predetermined point by the nut as it is being operated on by the cutters, a spring intermediate of the cone and the front wall or plate of the head, and mechanism intermediate of the latch mechanism and the cone whereby said cone is held normally forward by the latch mechanism against the power of the spring and released and thrown back when the latch mechanism is thrown out of engagement by the nut. 65

2. In a tap of the character described, a head or case provided with a suitable tail or shank, a conical cutter-holder adapted to slide in said head, cutters connected with said holder and extending through the head and adapted to be expanded by the forward movement of the cutter-holder, a spring normally compressed between the cutter-holder and front plate of the head, extensions connected with the cutter-holder and projecting through the rear wall of the head along the shank, a latch mechanism in the path of the nut as it is being operated on, mechanism slidingly supported by said shank in the path of said extensions and directly supporting the latch mechanism, and mechanism pivotally connected with the head and adapted to engage the mechanism in the path of the extensions and supporting the latch mechanism, for the purpose of returning simultaneously the cutter-holder and the latch mechanism into their original positions. 85

3. In a tap of the character described, a head or case provided with a suitable tail or shank, a conical cutter-holder adapted to slide in said head, cutters connected with said holder and extending through the head and adapted to be expanded by the forward movement of the cutter-holder, a spring normally compressed between the cutter-holder and front plate of the head, extensions connected with the cutter-holder and projecting through the rear wall of the head along the shank, a latch mechanism in the path of the nut as it is being operated on, a flanged hub adapted to slide on the shank and provided with a carrier-arm for supporting the latch mechanism, and a yoke-lever pivotally sustained by the head and adapted to move the flanged carrier-arm hub into engagement with the extensions from the conical cutter-holder and to yield when the latch is unlocked and the cutter-holder released and thrown back by the spring. 105

In testimony whereof I have signed my name to this specification in the presence of two subscribing witnesses.

THOMAS F. KEAN.
